US0D1052942S

(12) **United States Design Patent** (10) Patent No.: **US D1,052,942 S**
(45) Date of Patent: ** Dec. 3, 2024

(54) **TABLE**

(71) Applicant: **EDRA SPA**, Perignano (IT)

(72) Inventor: **Iacopo Emilio Foggini**, Perignano (IT)

(**) Term: **15 Years**

(21) Appl. No.: **35/518,816**

(22) Filed: **Oct. 6, 2023**

(80) **Hague Agreement Data**

Int. Filing Date: **Oct. 6, 2023**

Int. Reg. No.: **DM/232455**

Int. Reg. Date: **Oct. 6, 2023**

Int. Reg. Pub. Date: **Oct. 27, 2023**

(30) **Foreign Application Priority Data**

Apr. 18, 2023 (EM) 015018486-0001

(51) **LOC (14) Cl.** **06-03**

(52) **U.S. Cl.**

USPC **D6/696.1**

(58) **Field of Classification Search**

USPC D6/685, 686, 696, 696.1–696.7
CPC A47B 7/00; A47B 13/00; A47B 13/02;
A47B 13/04; A47B 13/06; A47B 13/08;
A47B 13/10; A47B 13/12; A47B 17/00;

A47B 21/00; A47B 2200/0001; A47B
2200/0011; A47B 2200/002
